UNITED STATES PATENT OFFICE.

ANTON OLEJNICZAK, OF CHICAGO, ILLINOIS.

CAR-COUPING.

1,228,696.

Specification of Letters Patent. Patented June 5, 1917.

Application filed February 16, 1917. Serial No. 148,964.

To all whom it may concern:

Be it known that I, ANTON OLEJNICZAK, a subject of the Czar of Russia, resident of Chicago, county of Cook, and State of Illinois, have invented certain new and useful Improvements in Car-Couplings, of which the following is a specification.

This invention relates to improvements in railway draw-bars, and has as its principal object the provision of means whereby a combined draw-bar and bumper is cushioned with respect to its connection with a car, the cushioning elements being so arranged as to absorb the shock which would otherwise be imparted to the car body.

This and other like objects are attained by the novel construction and combination of parts hereafter described and shown in the accompanying drawings, forming a material part of this specification, and in which:

Figure 1 is a bottom plan view of a car frame showing the application of the invention.

Fig. 2 is a vertical sectional view taken on the center line of the same.

Fig. 3 is a bottom plan view of the same, some of the parts being broken away and others shown in section and

Fig. 4 shows a detail of construction.

The underside of the car body is represented by the numeral 10, and has rigidly attached to it a longitudinally disposed strip 11, secured by means of transverse elements 12, which are also used to support the draw-bar elements.

Coupling heads 14, of any approved design, are secured in the longitudinal elements 11 at the ends by means of stems 15, which are slidably engaged in rigid plates 16, and formed at their inner ends with enlargements 17 to which are secured casings 20 open at their sides, and slideable on fixed transverse bars 21 attached to the longitudinal element 11.

Interposed in the pockets formed by the casing upon either side of the cross bars 21, are rigid plates 22 having between them heavy coiled springs 23, similar springs 24 being disposed between the corresponding plates 25, set in the pocket at the opposite side of the cross bars 21.

These springs are of sufficient strength to withstand the tractive force necessary to draw the car, and at the same time to resist

or take up the thrust of an impulse communicated to the draw-bar heads 14.

In addition, in order to minimize the shock, a centrally disposed spring 28 is contained in a bracket 29 secured midway of the car, the spring surrounding a portion of the enlarged bumper bars 30, connected by the stems 31 to heads 32, and held in slideable position by the brackets 33.

A similar head 35 is secured to the stem 36 slideable in the bracket 37, the opposite end of the stem being bifurcated and slidably engaged in the bracket 12 and held therein by the center pin 38, the fork ends being engaged with heads 40 to which are secured pins 41, the same passing through openings in the casings 20 and the contacting plates 25.

In operation, when one car or an engine is brought forcibly against another, the draw-bar heads 14 are forced inward toward the center of the car opposing the springs 23 and by reason of the rigid casing 20 part of the thrust is taken on the heads 40, transmitted through the elements 32 and 35 and bar 31 to the spring 28, so as to absorb the shock and cushion the action to a very considerable extent.

It will also be noticeable that should sufficient energy be exercised by the contacting car that the thrust effect will be further transmitted through the springs 28 to the opposite end of the car and eventually taken up by the fixed bars 21, while the pull of the car is entirely taken by the springs 24.

Having thus described my invention, what I claim as new, and desire to secure by Letters Patent, is:

In a combined draw-head and bumper, the combination with a rigid longitudinal support attached to the car frame, draw-heads slidably engaged at the ends of said support, casings connected to the inner ends of said draw-head, rigid cross-bars passing through said casing, springs disposed upon either side of said cross-bar within said casing, a spring centrally arranged of said support element, said spring being adapted to operate in both directions, independent bars interposed between said springs, and means for supporting said bars.

In testimony whereof I have affixed my signature this 5th day of February, 1917.

ANTON OLEJNICZAK.
